UNITED STATES PATENT OFFICE

SIGURD H. HELLAND, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS

BUILDER MECHANISM FOR SPINNING FRAMES

Application filed November 2, 1928. Serial No. 316,797.

This invention relates to machines for spinning yarn, and more particularly to means for automatically resetting the builder mechanism after the winding of a set of bobbins has been completed.

In such spinning machines, means is provided for gradually shifting the locus of movement of the ring rails upward as the bobbins are filled, so that the ring rail is reciprocated at its upper limit of movement when the winding of a set of bobbins is completed. It is then necessary to lower the ring rail before the winding of a new set of bobbins can be commenced.

This resetting operation has heretofore been performed manually, necessitating the personal attention of the spinner and causing a substantial loss of time.

It is the general object of my invention to provide improved automatic mechanism for resetting the builder mechanism of a spinning frame and for placing the mechanism in condition for renewed operations.

My invention further relates to arrangements and combinations of parts which will be hereinafter described and more particularly pointed out in the appended claims.

A preferred form of the invention is shown in the drawings in which—

Fig. 1 is a side elevation of my improved builder mechanism;

Fig. 2 is a plan view thereof, partly in section, and

Fig. 3 is an end view, looking in the direction of the arrow 3 in Fig. 2.

Referring to the drawings, I have shown a portion of a spinning frame 10, on which a builder lever 11 is pivoted to swing about a hollow stud 12 (Fig. 2) firmly fixed in the frame 10. A roll 14 is fixed on the side of the builder lever 11 and is engaged by a cam 15, mounted on the cam shaft 16, by which it is continuously rotated.

A chain 20 is secured to a disc 21 (Fig. 3) 45 rotatable on a stud 22 fixed in the builder

lever 11. A worm gear 24 is secured to the disc 21 and rotates therewith. The worm gear 24 is engaged by a worm 26 fixed on a worm shaft 27, rotatable in bearings in the builder lever 11 and having a ratchet wheel 30 secured to the front end thereof.

A pawl 31 (Fig. 3) is mounted on an arm 32 pivoted to swing about the axis of the worm shaft 27. The normal position of the arm 32 relative to the builder lever is determined by an adjustable stop screw 34 (Fig. 3) threaded in an offset projection 35 of the builder lever. The arm 32 is moved by gravity against the stop 34 when not otherwise actuated.

When the builder lever approaches its lower limit of movement, the arm 32 is engaged by a stop or abutment 40, adjustably secured in a slot 41 in a stand 42 secured to a cross member 43, which in turn is supported by the frame 10. As the builder lever is moved further downward, the arm 32 swings upward about the axis of the shaft 27, turning the ratchet 30, and partially rotating the worm 26 to wind down a small portion of the chain 20.

This action takes place intermittently, at every downward movement of the builder lever, and the amount of feed is so proportioned by adjustment of the stop screw 34 that the winding down of the chain 20 will correspond to the desired upward building of the yarn on the bobbins.

The parts thus far described are, in general, of the usual construction. It will be understood that the chain 20 is connected at its upper end by suitable levers to the usual lifter rods of the ring rails.

My invention relates particularly to the provision of improved mechanism for rotating the worm 26 in reverse direction to unwind the chain 20 and lower the ring rail at the time the machine is doffed and empty bobbins are placed on the spindles. For this purpose, the shaft 27 is extended rear-

ward and is provided with a threaded portion 50 on which a nut 51 is mounted. Rearward of the threaded portion 50 the shaft 27 is provided with a cylindrical portion extending freely through the hub of a bevel gear 52, rotatably mounted in a bearing 53 on the builder lever 11.

10 The bevel gear 52 meshes with a similar gear 54 (Fig. 2) mounted on a shaft 55 rotatable in the hollow stud 12 previously mentioned. A third bevel gear 56 is secured to the opposite end of the shaft 55 and is engaged by a bevel gear 57 on the lower end of a driving shaft 58. The shaft 58 is continuously rotated from any convenient part 15 of the machine.

20 A clutch member 60 (Fig. 1) is secured on the front end of the hub of the bevel gear 52, and is thus continuously rotated. A second clutch member 62 is slidably mounted on the cylindrical rear portion of the worm shaft 27, the member 62 being keyed to the shaft and its forward limit of movement being determined by a stop collar 63. Axial movement of the sliding clutch member 62 is determined by a yoke member 64, fixed on a rod 65, extending parallel to the worm shaft 27 and slidable in bearings on the builder lever 11. A spring 66 is interposed between the yoke member 64 and a collar 67 loose on the rod 65. The spring 66 when compressed rearwardly tends to move the clutch member 62 rearward, causing engagement thereof with the constantly rotating clutch member 60.

30 A latch 68 is pivoted at 69 on the builder lever and is provided with a shoulder 70, normally engaging the yoke member 64 and preventing rearward movement thereof. A spring 71 holds the latch 68 yieldingly in 40 operative position.

45 The nut 51 has an arm 75 extending upwardly therefrom, as shown in Fig. 1, and having a beveled or wedge-like upper end portion 76.

The operation of the parts thus far described is as follows:—

50 The intermittent feed of the ratchet wheel 30 by the pawl 31 rotates the work shaft 27 as indicated by the arrow in Fig. 1, and gradually moves the nut 51 rearward. The arm 75 first engages the collar 67, sliding the same along the rod 65 and placing the spring 66 under compression. Eventually, the beveled 55 end portion 76 of the arm 75 engages a roll 77 on the end of the latch 68 and raises the latch, thus releasing the yoke member 64, which immediately moves rearward under the influence of the spring 66 and causes the clutch member 62 to engage the rotating clutch member 60. The worm shaft 27 is thereupon rotated in the opposite direction, unwinding the chain 20 and moving the nut 51 toward the front end of the builder lever. 60

65 This operation is performed quickly and au-

tomatically, and without any attention on the part of the operator.

70 During this rewinding of the worm shaft 27, it is essential that the pawl 31 be out of engagement with the ratchet 30, and for this purpose I provide a rod 80 (Fig. 1) slidable in a bearing 81 on the builder lever and provided with a cone-shaped head 82 at its front end. At its rear end, the rod 80 is threaded to receive nuts 83 disposed at each side of an arm 84 projecting laterally from the sliding rod 65 on which the yoke member 64 is mounted. As the rod 65 is moved rearward to engage the clutch member 62 with the clutch member 60, the conical head 82 is drawn under the pawl 31, lifting the pawl out of operative engagement with the ratchet 30.

75 For restoring the latch 68 to operative position after the resetting operation, I have provided a collar 86 on the sliding rod 65 and engaged by a spring 87 abutting a collar 88 slidable on the rod 65 toward the arm 75 of the traveling nut 51. A latch 90 has a shoulder 91 to engage the collar 86 and also has a roll 92 to be engaged by the end 76 of the arm 75 projecting from the nut 51. A spring 93 holds the latch 90 yieldingly in operative position.

80 The collar 86 is so positioned on the rod 65 that the collar will be brought rearward of the shoulder 91 when the clutch member 62 is moved into engagement with the driving clutch member 60. Separation of the clutch members is thus prevented until the 95 nut 51 has been moved forward by reverse rotation of the worm shaft 27 to such a distance that the beveled end 76 engages the roll 92 on the latch 90. The latch 90 is then 100 raised, permitting forward sliding movement of the rod 65 by the spring 87, and disengagement of the clutch members 60 and 62. This forward movement brings the yoke member 64 in position for re-engagement by the shoulder 70 of the latch 68, thus returning the parts to their initial position, at the 105 same time removing the conical head 82 of the rod 80 from beneath the pawl 31.

110 I have thus provided mechanism operating entirely automatically for rewinding the worm shaft 27 in reverse direction to unwind the chain 20, for simultaneously interrupting the ratchet feed, and for thereafter restoring the ratchet feed when the chain 20 has been unwound to a predetermined point. 115 Any suitable mechanism may be provided for stopping the spinning frame, either manually or automatically, after the resetting of the builder mechanism has been completed.

120 Having thus described my invention and the advantages thereof, I do not wish to be limited to the details herein disclosed otherwise than as set forth in the claims, but what I claim is:—

125 1. In a builder mechanism for spinning

frames, a builder lever, a worm and worm shaft mounted thereon, pawl and ratchet mechanism effective to intermittently rotate said worm shaft in one direction, a continuously rotated driving member, a clutch adapted to connect said driving member to rotate said worm shaft in the reverse direction, a latch effective to hold said clutch inoperative, a second latch effective to hold said clutch operative, and means to alternately release one of said latches and cause effective engagement of the other latch.

2. The combination in a spinning frame as set forth in claim 1, in which said latter means comprises a nut mounted on a threaded portion of said worm shaft and movable axially thereby to engage and release one or the other of said latches as said nut approaches its opposite limits of travel.

20 3. The combination in a spinning frame as set forth in claim 1, in which a separate spring is provided for shifting said clutch to operative and to inoperative positions, and in which a member threaded on said 25 worm shaft alternately compresses said springs and releases the latch associated with each spring after compression of said spring.

4. In a builder mechanism for spinning frames, a builder lever, a worm and worm shaft mounted thereon, pawl and ratchet mechanism effective to intermittently rotate said worm shaft in one direction, a continuously rotated driving member, a clutch adapted to connect said driving member to 35 rotate said worm shaft in the reverse direction, a separate spring to move said clutch in each direction, a separate latch to prevent such movement in each direction, means to compress said springs alternately, and 40 means to release said latches alternately after the associated springs have been compressed.

5. In a builder mechanism for spinning frames, a builder lever, a worm and worm shaft mounted thereon, pawl and ratchet mechanism effective to intermittently rotate said worm shaft in one direction, a continuously rotated driving member, a clutch adapted to connect said driving member to 50 rotate said worm shaft in the reverse direction, and means to render said pawl inoperative when said clutch is engaged.

6. In a builder mechanism for spinning frames, a builder lever, a worm and worm shaft mounted thereon, pawl and ratchet mechanism effective to intermittently rotate said worm shaft in one direction, a continuously rotated driving member, a clutch adapted to connect said driving member to 55 rotate said worm shaft in the reverse direction, a slidable bar mounted adjacent said worm shaft and connected to said clutch to operate said clutch, means to move said bar with a snap action in each direction, and a 60 member threaded on said worm shaft effec-

tive to release said bar for such snap action.

7. The combination in a spinning frame as set forth in claim 6, in which a cam rod is connected to said sliding bar, said cam rod being effective to render said pawl inoperative when said bar is moved to engage said 70 clutch.

In testimony whereof I have hereunto affixed my signature.

SIGURD H. HELLAND.
